UNITED STATES PATENT OFFICE.

HOWARD D. COLMAN, OF ROCKFORD, ILLINOIS, ASSIGNOR, BY MESNE ASSIGNMENTS, TO BARBER-COLMAN COMPANY, OF ROCKFORD, ILLINOIS, A CORPORATION OF ILLINOIS.

LOOM.

Application filed May 6, 1921. Serial No. 467,496.

To all whom it may concern:

Be it known that I, HOWARD D. COLMAN, a citizen of the United States, residing at Rockford, in the county of Winnebago and 5 State of Illinois, have invented certain new and useful Improvements in Looms, of which the following is a specification.

This invention relates primarily to mechanical warp stop motions for looms, but 10 certain features of the invention are of general utility in looms.

Warp stop motions may be classified into two groups; those wherein the heddles have a detecting function and those wherein 15 the detecting function is performed by elements distinct from the harnesses, such elements being commonly termed "drop wires." Without attempting to set forth all the considerations which have restricted the commercial 20 use of warp stop motions, it may be stated that the principal objections to warp stop motions of the second mentioned class are the cost of drawing the warp through the drop wires, the expense and trouble of re- 25 moving the drop wires from the loom when warp replenishment is required, transporting the drop wires to warp-drawing or warp-tying machines and again installing them in the loom, and the additional work 30 caused the weaver when remedying conditions that have brought about a stoppage of the loom.

Warp stop motions of the first mentioned class may be subdivided into two mechanical 35 types; those wherein the heddle when functioning to stop the loom makes contact with a feeler or the like which forms no part of the harness, and those wherein the detecting element that cooperates with the heddle is 40 carried upon the harness. For various reasons stop motions of the first type have not gone into wide use. Stop motions of the second type have not, so far as I am aware, attained any commercial success. Among 45 the reasons why warp stop motions of the last mentioned kind have not been used commercially, are the liability of the harness-carried elements to injury in handling while out of the loom, the difficulty or practical 50 impossibility of preventing the heddles or the coacting detecting members from being rendered inoperative by lint or dirt, and the fact that the principles of organization were such that the necessary rigidity, durability

and proper adjustment could not be attained 55 and preserved.

The object of this invention, generally stated, is to produce a warp stop motion of the last mentioned type which shall not be apt to be damaged by such handling as loom 60 harnesses receive under mill conditions, which shall be durable, the operation of which shall not be liable to be affected by lint or dirt, which shall lend itself readily to varying requirements as to the sley of the 65 warp, the number of harnesses, etc., and which shall possess the necessary high degree of certainty and reliability of action.

In the accompanying drawings, Figure 1 is a front elevation, with some parts omitted, 70 of a loom embodying the features of this invention. Fig. 2 is a fragmental view taken from the left-hand side of Fig. 1. Fig. 3 is a view taken in the plane of line 3—3 of Fig. 1. Fig. 4 is a section on line 4—4 of 75 Fig. 3. Fig. 5 is a view taken in the plane of line 5—5 of Fig. 1. Fig. 6 is a fragmental front view of the stopping mechanism. Fig. 7 is a perspective view of one corner of a 80 heddle frame. Fig. 8 is a plan view of 85 a part of the stopping mechanism. Fig. 9 is a fragmental perspective view of the feeler shaft and the element that limits oscillation of the shaft. Fig. 10 illustrates the means for preventing end- 85 wise movement of the feeler shaft. Fig. 11 is a fragmental view of the stopping mechanism, looking from the left-hand side 90 of Fig. 1. Fig. 12 is a view similar to Fig. 11, but showing the parts in a different position. Fig. 13 is a fragmental perspective view of one of the heddle frames. Fig. 14 is a section on line 14—14 of Fig. 15. Fig. 15 is a fragmental illustration of a heddle that may be used in carrying out this invention. 95 Fig. 16 is a view of another form of heddle, with parts broken away to shorten the view. Fig. 17 is a section on line 17—17 of Fig. 16. Fig. 18 is a perspective view illustrating the operation of the detecting heddles. Fig. 19 is an enlarged sectional view to show the action of the heddle. Fig. 20 is an enlarged fragmental view of a repair or replacement heddle. Fig. 21 is a section on line 20—20 of Fig. 20. Figs. 22 and 23 illustrate a 105 means for suspending a harness consisting of two heddle frames. Fig. 24 shows a device for suspending a harness formed of

three heddle frames. Fig. 25 illustrates a member for connecting the lower portions of two heddle frames to the shedding motion. Fig. 26 is a detail view of the connecting member. Fig. 27 represents the manner of connecting a harness consisting of three heddle frames to the shedding motion. Fig. 28 is a detail view of the connector illustrated in Fig. 27. Figs. 29 to 32, inclusive, illustrate an alternative construction of the means for restoring the heddle cranks to initial position, Fig. 30 being a sectional view taken in the plane of line 30—30 of Fig. 31.

In the drawings, the invention is shown as applied to a loom of well-known construction, but it will be understood that the invention may be applied to looms of various types.

While any desired number of harnesses may be employed, I have, for the sake of simplicity, shown a two-harness loom, the harnesses being indicated at A in Fig. 1. Each harness may consist of any suitable number of heddle frames B (Fig. 13). In the present instance each heddle frame is a rigid metallic structure consisting of a top bar 1, a bottom bar 2 and end bars 3.

The means for reciprocating the harnesses to form the shed may be of the well-known or any preferred character. Herein the harnesses are shown as suspended from the ordinary harness roller 4 (Fig. 1) by means of straps 5 fastened to the set collars 6 and 7.

While the means for connecting the harnesses to the straps 5 may vary widely, the construction illustrated in Figs. 22 and 23 has been found satisfactory. As shown in said views each connector consists of a metallic loop 8 having an opening 9 through which the screw-threaded shank of a hook 10 extends freely, said hook being adapted to engage in openings in the strap 5. The loop rests upon a nut 11 on said shank. To the loop 8 is pivoted a depending metallic strap-like member 12 for each heddle frame comprised in the harness. At the lower end of the member 12 is a concave or hooked portion 13 adapted partially to embrace a bead or roll 14 on the upper edge of the bar 1, and to pass through a slot 15 in said bar just below the bead. To facilitate engagement of the heddle frame with the hook 13, said hook is made comparatively shallow, the parts being locked in engagement with each other by means of a latch 16 pivoted to the member 12 at 17 and having below said pivot a curved portion 18 adapted to engage the bead 14 and hold the latter in the hook 13. The upper arm of the latch 16 is made resilient and carries a locking pin 19 adapted to snap into a hole 20 in the member 12. By reason of the pivotal connection of the member 12 with the loop 8, the operator may easily spread the upper portions of the

heddle frames apart, if necessary, to determine which heddle has operated to stop the loom, to insert a new heddle, or for any other purpose.

In practice, the heddle frames B are made capable of being used in either the front or the rear harness, each heddle frame having slots 15 located in position for engagement by the suspending devices for either harness.

The lower bars of the heddle frames may be connected to the shedding mechanism in any desired manner. In the present embodiment of the invention, sheet metal loops 21 (Figs. 25 and 26) are employed, the ends of the arms of the loop being curved to form inturned hooks 22 adapted to pass through slots 23 in the bottom bar 2 and engage a bead 24 formed upon the lower edge of said bar. The lower or closed end of the loop 21 engage a U-shape fastening 25 (Fig. 1) attached to a bar 26 which is connected to the treadle (not shown) by means of a strap 27. The hooks 22 are made sufficiently deep to afford an effective engagement with the beads 24, and the resilience of the loop 21 holds the hooks 22 close together so that the heddle frames cannot become accidentally disengaged from the shedding motion. As indicated in Figs. 27 and 28, the loop may have any necessary number of hooks 22.

Referring now to Figs. 13 and 14: The heddle frames B contain metallic heddles 28. Each heddle consists of a flattened middle portion 29 having an eye 30 and two hooked ends or supporting portions 31, the portions 32 intermediate the hooked ends and the middle portion 29 being of less cross-sectional area than said hooked ends. The heddles herein shown are formed of wire bent to form the hooked ends 31, swaged to produce the relatively slender bodies 32 of circular cross-section, and flattened and perforated to produce the thread-receiving portion. As shown in Fig. 16 the eye 30 is of elongated shape, the end walls of the eye being curved, and all the edges of the eye and the flattened portion 29 being rounded to avoid chafing or wearing the threads. As indicated in Fig. 17 the perforated portion 29 lies in a plane which extends at an acute angle to the plane of the supporting portions 31 in order that the thread may pass through the eye without bending.

The metal of which the bars 1 and 2 of the heddle frame are formed is bent to provide two rails 33 and 34, respectively, for engagement by the hooked ends of the heddles. The distance between the upper edge of the upper rail 33 and the lower edge of the lower rail 34 is somewhat less than the distance between the closed ends of the hooked portions 31, thereby allowing longitudinal movement of the heddles in relation

to the frames B, but the distance between the upper edge of the rail 33 and the lower edge of the rail 34 is somewhat greater than the distance between the closed end of one hook 31 and the free end of the opposite hook, thus holding the heddles in the frame. The rails 33 and 34, in conjunction with the adjacent portions of the bars 1 and 2, form channels 35 which extend from end 10 to end of the bars. Inasmuch as these channels extend to the ends of the frame, heddles may be inserted into or removed from the frame at either end thereof. At such times as the heddles should be prevented from slipping out of the frame, the channels 35 may be closed in any preferred manner. Herein are shown screws 35^a engaging the bars 1 and 2 and extending across the ends of the channels 35 at the 20 upper right-hand corner and the lower corners of the frame. The means for closing the channel 35 at the upper left-hand corner of the frame will be described hereinafter.

25 If described, the supporting hooks of the heddles may be flattened on opposite sides, as shown at 31^a, in Figs. 14 and 15, thereby permitting a larger number of heddles to be placed in the frame, and obviating 30 any tendency of the hooks to become wedged in the channels 35 in the operation of moving heddles into or out of the frame.

35 Figs. 20 and 21 illustrate a form of heddle which may be used whenever it becomes necessary to insert a heddle into a made-up harness, as, for example, when a damaged heddle must be replaced. The repair heddle shown in Figs. 20 and 21 has a hook 31' comprising a relatively movable portion 41^a which may be moved into position to clear the rail 33 in the operation of inserting the heddle and then swung down behind said rail. Herein the portion 41^a is represented as pivoted to the opposite member of the hook. As shown in Fig. 20, the upper portion of the heddle has a head 41^b having a tapering bearing 41^c to receive a correspondingly tapered pivot 41^d on the hook-portion 41^a. The pivot is held in its bearing with a considerable degree of friction by riveting the end of said pivot.

40 It is desirable to make the heddle frame as light as possible, and to reduce its thickness (i. e., its dimension from front to rear of the loom) to a minimum. In the construction disclosed in Figs. 13, 18 and 19, the frame is illustrated as made of sheet metal of sufficiently heavy gage so that the edges upon which the hooks 31 bear are 45 thick enough to resist the stresses arising in operation and in handling. These edges may be hardened to resist wear. If it be desirable to use metal of such light gage that the edges of the rails 33 and 34 would 50 not be sufficiently rigid without reinforce-

ment, they may be reinforced by means of a roll or bead, and this roll may be hardened or may be covered with a hardened bead.

55 Upon reference to Fig. 18 it will be apparent that when the heddle frame is raised, gravity and the tension of the warp threads hold the upper hooks 31 in contact with the upper edge of the rail 33, and that when the heddle frame is lowered, the threads lift 75 the upper hooks 31 away from the upper edge of the rail 33 to the extent permitted by the lower hooks 31. If there be a broken or excessively slack thread in the lower sheet of threads when the heddle frame descends, the heddle corresponding to that thread will not be lifted. Means is provided to detect any such failure of a heddle to rise with relation to its heddle frame, and to actuate mechanism for stopping the 80 loom. The detector means herein shown comprises an oscillatory rod or shaft 38 mounted within a bearing 39 formed integral with the top bar 1. Preferably the bearing 39 is approximately as long as the 85 shaft 38 so as to encase and support the shaft throughout substantially the length of the latter, whereby the shaft is effectively supported against deflection and protected from dirt and lint. The fact that the 90 feeler shaft is carried by the upper bar of the heddle frame contributes to an important extent in keeping it free from lint and dirt, as such matter accumulates much more rapidly upon the lower portion of the 95 harness than upon the upper part.

100 A groove or recess is formed in the feeler shaft 38 in any suitable manner, so as to provide a shoulder or flange 40, the length of which is at least equal to the width of 105 the series of heddles. Means is provided which normally is effective to turn the feeler shaft 38 in the direction to move the shoulder 40 transversely of the channel 35 after the heddle frame has completed its downward movement. If, however, any heddle fails to rise with relation to the heddle frame during the descent of the latter, the portion 41 (Fig. 19) of the hook 31 of said heddle remains in the path of movement of 110 the shoulder 40 and thus prevents the feeler shaft 38 from turning to an effective extent.

115 The means for pivotally moving the feeler shaft 38 to press the shoulder 40 against the portion 41 of any heddle corresponding to a broken or excessively slack thread may partake of various forms. Herein the shaft 38 is provided at one end with a crank 42 adapted to engage suitable means for giving the shaft a "feeling" movement during the dwell at the end of the descent of the heddle frame and a restoring movement when the heddle frame rises. In wide looms, 120 where the length of the feeler shaft 38 may 125

be so great that the shaft might twist excessively if the functioning heddle were relatively remote from the crank, there may be a crank and crank-turning means at each 5 end of the shaft.

Any suitable means may be used to limit the extent of oscillation of the feeler shaft 38, as, for example, that shown in Figs. 7, 9 and 10. 43 is an integral sheet-metal element comprising a web 44 adapted to lie against the end of the bar 1, flanges 45 and 46 to lie at opposite sides of and closely embrace the rail 33, a resilient arm 46' adapted to extend along the bar 1 just below the roll 14 and having a locking pin 47 adapted to enter a hole 48 (Fig. 7) in the bar 1, and two lugs 49 and 50 on the web 44 adapted to engage the crank 42 and thus limit the pivotal movement of the feeler shaft. On 20 the upper end of the web 44 is a stud 51 (Fig. 9) removably fitting within the end of the roll 14. An opening 52 in the web 44 provides clearance for the shaft 38. On said shaft is a collar 53 adapted to lie between the web 44 and the end of the bearing 39 and serving to prevent longitudinal movement of the shaft. Upon removing the pin 47 from the hole 48 the element 43 and the shaft 38 may be withdrawn from the 30 heddle frame. When desired, the shaft 38 may be readily separated from the element 43 by withdrawing the crank 42 through the opening 52.

It will be seen that the web 44 serves to 35 close the adjacent end of the upper channel 35.

The means to impart the restoring movement to the feeler shaft may be of any preferred construction. In Figs. 2 and 3 there 40 is shown a rod 54 attached to a stem 55 which is vertically adjustable in a bracket 56 fixed to the loom framework. The rod 54 is long enough to lie in the path of movement of the cranks 42 of all the harnesses 45 in the loom. The portions of said rod which are engaged by the cranks are located at the proper heights with reference to the throw of the cranks and the length of movement of the harnesses. Inasmuch as the 50 rear harness has a longer movement than the front harness, that part of the rod 54 which is engaged by the cranks of the rear harness is higher than the portion of said rod which operated the cranks of the front 55 harness.

The means for producing the feeling movement of the feeler shaft may be varied within wide limits without departing from the spirit of the invention. In Fig. 4 is 60 shown a slide 57 mounted in a vertical guide 58 forming part of a bracket 58 connected to the loom framework. A coiled contractile spring 59 is adjustably attached at one end to the bracket 56 and at its other end 65 to the upper end of the slide 57. To the

lower end of the slide is connected a rod 60. The lower portion of the rod 60 passes freely through an opening in the arm 61 (Fig. 11) of a bell-crank lever 62. The lever 62 is pivoted at 63 upon an arm 64. Normally 70 the spring 59 holds the arm 61 against a stop screw 64^a on the arm 64. The latter is fixed upon a rock shaft 65 mounted in the loom framework. Rigid with the shaft 65 is an arm 66 carrying a roller 67 that runs upon a cam 68 fixed to a shaft 69 of the loom, as, for example, the shaft on which the shedding cams are mounted. On the lower end of the rod 60 is a collar 70, the position of which may be adjusted by a nut 71. 80 71^a is a lock nut. A bell-crank lever 72 is loosely or pivotally mounted on the shaft 65 and comprises two arms 73 and 74. Gravity normally holds the bell crank lever 72 in the position shown in Fig. 11, its position being determined by contact of a stop screw 75 on the arm 73 with a part of the loom framework. The free end of the arm 73 is adapted to be engaged by a shoulder 76 on the arm 61^a of the bell-crank lever 62. The free end of the arm 74 carries a member 77 which is adjustably secured in place by a screw 77^a passing through a slot 77^b in said member. The member 77 normally is adjacent to the lower arm 78 of the shipper handle 79, the latter being pivotally supported at 80. The shipper handle extends through a slotted part 81 having a locking shoulder 82 against which the shipper handle is normally held by a coiled contractile spring 83. The shipper handle engages one arm 84 of a lever 85 pivoted at 86 to the loom framework. The other arm of said lever is connected to a rod 87 which is arranged to operate the belt shifter 88. The shipper handle and its connections to the belt shifter are of common construction, and any preferred devices may be substituted therefor. 90 95 100 105 110

Referring now to Figs. 2, 3, 8 and 18: 89 is a plate adapted to engage the cranks 42 of all the harnesses of the loom, said plate being preferably adjustably mounted on the slide 57. Herein the plate 89 is shown as having an attaching portion 90 which is pivoted to the slide at 91, said portion being secured to the slide in adjusted position by means of a nut 92 turned on a stud 93 which extends through a slot in the portion 90 and is fixed to the slide 57. The different parts of the plate 89 are arranged at the proper relative heights to engage with the cranks 42 of the heddle frames. 115 120 125

In operation, the arm 64 draws the plate 89 down, the plate being in its lowest position by the time the harness completes its down stroke. During the dwell following the down stroke of the harness, the arm 64 rises, and the spring 59 raises the plate 89 and turns the cranks 42 of said harness up 130 against the stop 49, if all of said cranks be

free to turn. If, however, any of said cranks be prevented by a dropped heddle from turning, the plate 89 will be unable to rise; and as the arm 64 rises the bell crank 5 62 will turn by gravity on its pivot 63, whereby the shoulder 76 is swung under the end of the arm 73. In the continuing upward swing of the arm 64 the shoulder 76 engages and lifts the arm 73, thereby forcing the member 77 against the shipper handle, and freeing the latter from the locking shoulder 82, whereupon the spring 83 acts to shift the belt that drives the loom.

It will be noted that the feeling movement of the shaft 38 does not occur until after the down stroke of the harness has been completed, at which time the maximum tension has been placed upon the threads, thus avoiding stoppages which might be caused by threads which are not excessively slack if the feeling movement took place during the down stroke.

It is advantageous to feel for a dropped heddle at the conclusion of the down stroke, 25 rather than during or after the up stroke, since in the latter case it is necessary to employ springs or their equivalent to place the heddles in position to coact with the feeler element upon breakage or excessive slackening of threads.

It is desirable, when starting the loom with a new warp, or when restarting the loom after an automatic stoppage, to be able to render the warp stop motion ineffective for a time, as, for example, while slackness in the threads is being taken up. To disable the stop motion herein shown, it is merely necessary to loosen the set screw 77^a (Fig. 11). The arm 74 may then oscillate without operating the shipper handle 79. When the stop motion is to be again made effective, the member 77 is properly located on the arm 74 and secured in place by tightening the screw 77^a.

An alternative construction of the feeler-shaft restoring means is illustrated in Figs. 29 to 32. As therein shown, the bracket 58^a that provides the guide 58' for the slide 57 also comprises a vertically extending sleeve 94. A post 95 is longitudinally and rotatively adjustable in said sleeve, being held in the desired position by set screws 96. The upper end of the post 95 is bent to form a horizontal arm 97. A bracket 98 has a split hub or sleeve which is clamped upon the arm 97 whereby the bracket 98 is adjustable horizontally and rotatively. The bracket 98 projects rearwardly, and carries a bar 99. The portion of the bar 99 which extends forwardly of the bracket 98 is arranged to be engaged by the cranks 42^a. The rear end of the bar 99 is pivoted or loosely connected to the rear end of the bracket 98 by means of a stud 100 on the bracket projecting through an opening in

the bar. At a point between the stud 100 and the forward end of the bracket 98, a bolt 101 engages the bar, said bolt extending freely through an opening in the bracket. A coiled expansive spring 102 surrounds the bolt 101 and bears against the lower side of the bracket and a washer on the bolt, the position of the washer being determined by a nut 103.

In the upward movement of the harness, 75 the cranks 42^a strike the lower side of the bar 99 and are caused to swing into contact with the stops 50, the bar 99 yielding against the pressure of the spring 102 as shown by full lines in Fig. 30, so as to obviate excessive strain on the parts and avoid the necessity of extreme accuracy in the positioning of the bar.

If the operator should inadvertently hang the harnesses so that the cranks 42^a are 85 above the bar 99, the latter will yield when the loom is started up, the bar 99 fulcruming on the front end of the bracket 98 as indicated by dotted lines in Fig. 30, whereby breakage is avoided.

As shown in Figs. 29, 31 and 32, the bracket 58^a provides means for supporting the spring 59 that actuates the feeler shafts.

It will be seen that the warp stop motion herein shown is simple and rugged in 95 construction. Co-action between the heddles and the feeler shaft is not dependent upon springs or other parts of variable nature and is not likely to be affected by lint or dirt. The portion 41 of the heddle, which is engaged by the feeler shaft 38 when the heddle functions to stop the loom, is effectively supported by the abutment or rail 33, thus definitely holding the feeler shaft 38 in the position it should occupy at such a 100 time. The rail 33 supports the portions 41 against stresses tending to shear or bend said portions. The shaft 38 may be made sufficiently heavy to resist the torsional 105 stresses arising in looms of ordinary width, 110 while in wide looms the shaft may have a crank at each end, if desired.

The construction of the heddle frame and the feeler shaft is such that they are not apt to be damaged by such handling as harnesses receive when out of the loom. If the crank 42 should be damaged or if the feeler shaft should require cleaning, the shaft may be readily removed from the heddle frame by first disengaging the locking stud 47 from 115 the opening 48.

The heddles are of such character that they may be conveniently handled by the positioning, threading and distributing mechanisms of a warp-drawing machine.

It will be seen that the parts which directly coact with the detecting heddles are mounted upon the heddle frames. This fact simplifies the application of the invention to looms having various numbers of heddle 120 125 130

frames, since the parts that transmit the stopping impulse to the shipper handle may be easily made capable of co-action with any desired number of heddle frames.

5 The invention may be readily applied to existing looms, the brackets 56 and 58 (or the bracket 58^a) being adapted for attachment to the loom framework, and the cam 68 and levers operated thereby being arranged to be mounted upon shafts which are present in ordinary looms.

In ordinary looms of the prior art, the heddle frames have been attached to the harness roller by means including screw eyes in the harnesses. These screw eyes do not bear a fixed relation to the harnesses and, moreover, they are subject to relatively rapid wear because of the small area of the supporting surfaces of the eyes. Consequently the distance from the heddle eyes to the supporting surfaces of the screw eyes varies considerably. It is therefore usually necessary to regait the loom, that is to say, to adjust the straps whereby the harnesses 20 are attached to the harness roller and the shedding motion, whenever a new warp is put into the loom. On certain classes of work it sometimes takes a day or two to effect a satisfactory regaiting of the loom, 25 the product in the meantime being imperfect. With the construction herein shown the necessity for regaiting is obviated. The heddles being made by automatic machinery, there is very little variation in the distance 30 between the eye 30 and the hooks 31. The heddle frame also may be accurately made and therefore the total variation in the heddles and the frame is very small. The area of contact between the hooks 13 and 22 and 35 the heddle frames is relatively large and the contacting surfaces may be hardened, thus reducing wear to a minimum. Since the distance between the heddle eyes and the top roll 14 and the distance from the heddle 40 eyes to the bottom roll 24 are approximately the same in all heddle frames and remain substantially constant, it will be evident that any set of harnesses may be substituted for another without necessitating the regaiting 45 of the loom.

I believe myself to be the first to produce a really practical mechanical warp stop motion of the class wherein the devices that coact with the heddles are carried by the 50 harnesses, and desire the appended claims to be construed broadly.

I claim as my invention:

1. A heddle frame having a rail and means co-acting therewith to form a longitudinal 55 channel opening upon the end of the frame, and a series of heddles having hooked ends adapted to bear upon the edge of said rail, each of said hooked ends comprising a portion extending into said channel, and feeler 60 means to engage said portions.

2. A heddle frame having a metallic upper element formed of sheet metal bent to provide a top bar, a rail and a shaft bearing extending longitudinally of the heddle frame, said bar and rail forming between 70 them a channel extending longitudinally of the heddle frame above said bearing.

3. A heddle frame having means to support a full complement of heddles, a shaft bearing on said frame extending the entire 75 width of the series of heddles, and a feeler shaft supported in said bearing and adapted to engage said heddles.

4. A heddle frame comprising top, bottom, and end bars, the bottom bar comprising a metallic horizontal rail which is spaced from the remainder of the bottom bar to form a channel extending longitudinally of the bottom bar, the top bar comprising a metallic horizontal rail which is spaced from 85 the remainder of the top bar to form a channel extending longitudinally of the top bar, the lower portion of the last mentioned channel communicating with a bearing extending longitudinally of the top bar, an 90 oscillatory feeler shaft lying within said bearing, said shaft having a longitudinal shoulder, a series of heddles having hooked lower ends which are arranged to bear upon the lower edge of the bottom rail, and 95 hooked upper ends which are arranged to bear on the upper edge of the upper rail and having portions lying within the channel of the top bar, said portions being adapted to lie between said shoulder and said upper rail and thereby interfere with turning movement of said shaft, the distance between the upper edge of the upper rail and the lower edge of the lower rail being somewhat less than the distance between the 100 closed ends of the hooks of a heddle, but somewhat greater than the distance between the closed end of one hook and the free end of the opposite hook of a heddle.

5. A heddle frame comprising top, bottom and end bars, the bottom bar comprising a metallic horizontal rail which is spaced from the remainder of the bottom bar to form a channel extending longitudinally of the bottom bar, the top bar comprising a metallic horizontal rail which is spaced from the remainder of the top bar to form a channel extending longitudinally of the top bar, a series of heddles having hooked lower ends which are arranged to bear upon the lower edge of the bottom rail, and hooked upper ends which are arranged to bear on the upper edge of the upper rail, the distance between the upper edge of the upper rail and the lower edge of the lower rail being somewhat less than the distance between the closed ends of the hooks of a heddle, but somewhat greater than the distance between the closed end of one hook and the free end of the opposite hook of a heddle.

6. A heddle frame comprising a metallic horizontal upper rail and a metallic horizontal lower rail, a series of heddles having hooked lower ends which are arranged to bear upon the lower edge of the lower rail, and hooked upper ends which are arranged to bear on the upper edge of the upper rail, the distance between the upper edge of the upper rail and the lower edge of the lower rail being somewhat less than the distance between the closed ends of the hooks of a heddle, but somewhat greater than the distance between the closed end of one hook and the free end of the opposite hook of a heddle. 70
- 10 7. A heddle frame comprising top, bottom, and end bars, the top bar being formed of sheet metal bent to provide a horizontal rail which is spaced from the remainder of the top bar to form a channel extending from end to end of the top bar, whereby heddles may be inserted into or removed from the heddle frame at either end of said top bar, removable means for closing the 75 ends of said channel, the lower portion of said channel being enlarged to form a bearing extending longitudinally of the top bar, an oscillatory feeler shaft lying within said bearing, said shaft being longitudinally grooved to provide a shoulder, a series of heddles the lower ends of which are engaged with the bottom bar and the upper portions of which have hooked ends providing portions lying within said channel and adapted to extend into the groove in said shaft and thus lie between said shoulder and said rail and thereby interfere with turning movement of said shaft. 80
- 20 8. A heddle frame comprising top, bottom, and end bars, the top bar being formed of sheet metal bent to provide a horizontal rail which is spaced from the remainder of the top bar to form a channel extending longitudinally of the top bar, the lower portion of said channel being enlarged to form a bearing extending longitudinally of the top bar, an oscillatory feeler shaft lying within said bearing, said shaft being longitudinally grooved to provide a shoulder, a series of heddles the lower ends of which are engaged with the bottom bar and the upper portions of which have hooked ends providing portions lying within said channel and adapted to extend into the groove in said shaft and thus lie between said shoulder and said rail and thereby interfere with turning movement of said shaft. 85
- 25 9. A heddle frame comprising top, bottom and end bars, the top bar being of metal and comprising a horizontal rail which is spaced from the remainder of the top bar to form a channel extending longitudinally of the top bar, the lower portion of said channel communicating with a bearing extending longitudinally of the top bar, an oscillatory feeler shaft lying within said bearing, said shaft having a longitudinal shoulder, a series of heddles the lower ends of which are engaged with the bottom bar and the upper portions of which have hooked ends arranged to bear on the upper edge of said rail and having portions lying within said channel, said portions being adapted to lie between said shoulder and said rail and thereby interfere with turning movement of said shaft. 90
- 30 10. A heddle frame comprising a metallic horizontal upper rail and bottom and end bars, a bearing extending longitudinally of the upper rail, an oscillatory feeler shaft lying within said bearing, said shaft having a longitudinal shoulder, and a series of heddles having hooked upper ends which are arranged to bear on the upper edge of the upper rail, the free ends of said hooks being adapted to lie between said shoulder and said upper rail and thereby interfere with turning movement of said shaft. 95
- 35 11. A heddle frame comprising a top bar formed of sheet metal bent to provide a horizontal rail which is spaced from the remainder of the top bar to form a channel extending from end to end of the top bar, whereby heddles may be inserted into or removed from the heddle frame at either end of said top bar, the lower portion of said channel being enlarged to form a bearing extending longitudinally of the top bar, an oscillatory feeler shaft lying within said bearing, a crank on one end of said shaft, and removable means for closing the ends of said channel, the means for closing one end of said channel consisting of a sheet metal element comprising a web adapted to lie against the end of the top bar, flanges to lie at opposite sides of said rail, a resilient arm adapted to extend along the top bar and having a locking pin adapted to enter a hole in said top bar, and two lugs on said web adapted to engage said crank and thus limit the pivotal movement of the feeler shaft. 100
- 40 12. A heddle frame comprising a top bar formed of sheet metal bent to provide a horizontal rail which is spaced from the remainder of the top bar to form a channel extending longitudinally of the top bar, the lower portion of said channel being enlarged to form a bearing extending longitudinally of the top bar, an oscillatory feeler shaft lying within said bearing, a crank on one end of said shaft at one end of said channel, and removable means for closing the other end of said channel. 105
- 45 13. A heddle frame having a top bar comprising a horizontal rail which is spaced from the remainder of the top bar to form a channel extending longitudinally of the top bar, the lower portion of said channel being enlarged to form a bearing extending longitudinally of the top bar, an oscillatory 110
- 50 14. A heddle frame comprising a top bar formed of sheet metal bent to provide a horizontal rail which is spaced from the remainder of the top bar to form a channel extending longitudinally of the top bar, the lower portion of said channel being enlarged to form a bearing extending longitudinally of the top bar, an oscillatory feeler shaft lying within said bearing, a crank on one end of said shaft at one end of said channel, and removable means for closing the other end of said channel. 115
- 55 15. A heddle frame having a top bar comprising a horizontal rail which is spaced from the remainder of the top bar to form a channel extending longitudinally of the top bar, the lower portion of said channel being enlarged to form a bearing extending longitudinally of the top bar, an oscillatory feeler shaft lying within said bearing, a crank on one end of said shaft at one end of said channel, and removable means for closing the other end of said channel. 120
- 60 16. A heddle frame comprising a top bar formed of sheet metal bent to provide a horizontal rail which is spaced from the remainder of the top bar to form a channel extending longitudinally of the top bar, the lower portion of said channel being enlarged to form a bearing extending longitudinally of the top bar, an oscillatory feeler shaft lying within said bearing, a crank on one end of said shaft at one end of said channel, and removable means for closing the other end of said channel. 125
- 65 17. A heddle frame having a top bar comprising a horizontal rail which is spaced from the remainder of the top bar to form a channel extending longitudinally of the top bar, the lower portion of said channel being enlarged to form a bearing extending longitudinally of the top bar, an oscillatory feeler shaft lying within said bearing, a crank on one end of said shaft at one end of said channel, and removable means for closing the other end of said channel. 130

feeler shaft lying within said bearing, and a crank on one end of said shaft.

14. A heddle frame comprising a top bar formed of sheet metal bent to provide a horizontal rail which is spaced from the remainder of the top bar to form a channel extending longitudinally of the top bar, one end of said channel extending to one end of said top bar, whereby heddles may be inserted into or removed from the heddle frame at said end of said top bar, and removable means for closing said end of said channel.

15. A heddle frame comprising a top bar formed of sheet metal bent to provide a horizontal rail which is spaced from the remainder of the top bar to form a channel extending from end to end of the top bar whereby heddles may be inserted into or removed from the heddle frame at either end of said top bar, and removable means for closing the ends of said channel. 15 20

In testimony whereof, I have hereunto set my hand.

HOWARD D. COLMAN.
